UNITED STATES PATENT OFFICE.

WALTER E. HUENEFELD, OF CINCINNATI, OHIO.

HYDROCARBON-BURNER.

1,070,609.

Specification of Letters Patent. Patented Aug. 19, 1913.

Application filed May 15, 1913. Serial No. 767,948.

To all whom it may concern:

Be it known that I, WALTER E. HUENEFELD, of Cincinnati, in the county of Hamilton and State of Ohio, have invented certain new and useful Improvements in Hydrocarbon-Burners; and I do hereby declare the following to be a full, clear, and exact description of the invention, such as will enable others skilled in the art to which it applies to make and use the same.

This invention relates to improvements in hydrocarbon burners,—the object of the present invention being to provide simple and efficient wick-limiting means which can be quickly and cheaply made simultaneously with the forming of one of the shells of the combustion chamber member, with which latter, said wick-limiting means are movable vertically with respect to the wick tube member.

With this object in view, the invention consists in certain novel features of construction and combinations of parts as hereininafter set forth and pointed out in the claims.

In the accompanying drawings, Figure 1 is a sectional view (partly in elevation) showing a hydrocarbon burner, embodying my improvements, and Fig. 2 is a perspective view, partly in section, showing the wick-limiting devices at the lower end of the inner shell of the combustion chamber member.

1 represents the wick-tube member and 2 the combustion chamber member. The wick-tube member comprises concentric tubes or cylinders 3—4 forming a wick chamber between them to receive a wick 5. The outer wick tube 4 is provided at its upper end with an outwardly projecting depressed flange or seat 6 and the inner wick tube 3 is provided at its upper end with an inwardly projecting depressed seat 7.

The combustion chamber member comprises foraminated shells 8—9 spaced from each other to form a combustion chamber 10 between them which is in line with the wick. The shells 8—9 are inclosed by a casing 11 which is spaced from the outer shell 8 and secured to said shells in any suitable manner. The upper end of the casing is open and its lower end is provided with an inwardly projecting perforated flange 12.

The lower end of the shell 8 is seated (when the parts are in their normal positions) upon the outer depressed flange 6 at the upper end of the outer wick tube 4, and

the inner shell 9 is seated upon the inwardly projecting flange 7 at the upper end of the inner wick tube 3.

The inner foraminated shell 9 is notched at its lower end to form an annular series of lugs or fingers 13. This notched lower edge of the inner shell is bent upwardly against the outer face of the shell and the lugs or fingers 13 are bent outwardly to form radial wick limiting devices integral with the shell 9 and disposed transversely in the lower portion of the combustion chamber 10 in the path of the wick.

The combustion chamber member is provided with an extension cylinder 14 which depends into the space within the inner tube of the wick-tube member and co-operates with the inwardly projecting flange 7 at the upper end of the inner wick tube, to guide the combustion chamber member, when the same is moved vertically.

The extension cylinder is enlarged at its upper end as indicated at 15 and enters within the lower portion of the inner foraminated shell 9, in which it is secured somewhat above the lower edge thereof. A perforated diaphragm 16 is located within the enlargement 15 of the extension cylinder and is provided with a peripheral flange 17 fitting tightly within said enlargement. Somewhat below the enlargement 15, the extension cylinder 14 is provided with a plurality of holes 18, and a short distance below these holes, an imperforate diaphragm 19 is secured within the extension cylinder.

The lower end of the extension cylinder is provided with suitable engaging means to co-operate with cam arms 20 secured within the wick-tube member for locking the combustion chamber member in normal position and for raising and propping said combustion chamber member when the latter is turned, or partially rotated. The specific construction of these devices does not constitute a part of my present invention, the same being covered by my copending application filed even date herewith and designated by Serial No. 767,947, and hence a specific description of said details herein is not essential,—it being sufficient for the purpose of this case that some means be provided for raising and lowering the combustion chamber so that the wick-limiting devices shall be moved simultaneously with the movements of the combustion chamber member.

It will be observed that with my improvements, the wick-limiting lugs or fingers are integral with the lower end of the inner shell of the combustion chamber member and are therefore movable with the same away from or toward the wick, but when the burner is in operation, the limiting devices may be in more or less close proximity to the wick (according to the adjustment of the latter) without detracting from the efficiency of the flame on the wick.

Having fully described my invention what I claim as new and desire to secure by Letters-Patent, is:—

15 1. In a hydrocarbon burner, the combination of a wick tube member, and foraminated shells forming a vertically movable combustion chamber member, one of said shells having a notched lower portion forming a plurality of fingers integral therewith and disposed transversely in the combustion

chamber between said shells and in the wick path, said fingers constituting wick limiting means.

2. In a hydrocarbon burner, the combination of a wick-tube member and a vertically movable combustion chamber member comprising spaced foraminated shells forming a combustion chamber between them, one of said shells having its lower end bent upon itself and provided with an annular series of integral wick-limiting fingers disposed transversely in the combustion chamber in the path of the wick.

In testimony whereof, I have signed this specification in the presence of two subscribing witnesses.

WALTER E. HUENEFELD.
